[57] CLAIM

The ornamental design of a housing for a telephone amplifier, as shown and described.

DESCRIPTION

FIG. 1 is a front, top and right side perspective view of a telephone amplifier showing our new design;

FIG. 2 is a top plan view;

FIG. 3 is a sectional view of the grille taken along line 3—3 in FIG. 2;

FIG. 4 is a sectional view thereof taken along line 4—4 in FIG. 2;

FIG. 5 is a right side elevational view;

FIG. 6 is a front elevational view; and

FIG. 7 is a rear elevational view.

FIG. 1
